United States Patent Office

Des.241,565
Patented Sept. 21, 1976

241,565

AERIAL TOY

Lester V. Molenaar, Box 777, W. Highway 40,
Willmar, Minn. 56201

Filed Apr. 7, 1975, Ser. No. 565,526

Term of patent 14 years

Int. Cl. D21—01

U.S. Cl. D34—15 HS

FIG. 1

FIG. 2

FIG. 3

FIG. 4

FIG. 1 is a top plan view of an aerial toy showing my new design;

FIG. 2 is a side elevational view thereof;

FIG. 3 is a bottom plan view thereof; and

FIG. 4 is a cross sectional view of FIG. 3 taken on line 4—4.

I claim:

The ornamental design for an aerial toy, substantially as shown and described.
